(57) **CLAIM**

The ornamental design for Mars exploration rover Athena, as shown and described.

DESCRIPTION

The invention described herein was made in the performance of work under a NASA contract, and is subject to the provisions of Public Law 96-517 (U.S.C. 202) in which the Contractor has elected to retain title.

FIG. 1 is a perspective view of a Mars exploration rover Athena according to our new design;

FIG. 2 is a first side elevational view thereof;

FIG. 3 is a front elevational view thereof;

FIG. 4 is a second side elevational view thereof;

FIG. 5 is a rear elevational view thereof;

FIG. 6 is a top view thereof; and,

FIG. 7 is a bottom view thereof.
